UNITED STATES PATENT OFFICE

THEODOR CURT WAGNER, OF CHEMNITZ, GERMANY

ELECTRIC STOP MOTION FOR LOOMS

Application filed September 4, 1928, Serial No. 303,860, and in Germany May 7, 1928.

My invention relates to electric stop motions of the type used in looms. In this art the stop motion has an important part, since it is indispensable for an economically satisfying operation of the loom to have it stopped as quickly as possible upon occurrence of a breakage of a warp-thread. Furthermore, care must be taken to remove the warps and to fit up new warps as quickly as possible.

Electric stop motions are to be preferred over mechanical ones due to their simplicity. The electric stop motions hitherto known, however, have great drawbacks because specially punched lamellas are required which not only complicate the entire mechanism, but also render the attendance difficult, because upon tearing, the thread must not only be drawn through the eye of the heddle but also through that of the lamella, this threading taking place at two different places and therefore requiring at least a double manipulation. In the same manner the work of removing and filling-up of new warps is multiplied.

The required reliability is further not attained by following the proposal to design the upper or lower bar of the leaf as a conductor and to arrange therein and insulated therefrom another conductor, which both conductors are interconnected owing to the position the end eye of the heddle referred to takes upon breakage of a thread, so that when current is supplied to the conductors, a circuit is closed that stops the loom. In arrangements of this type the closure of the circuit sometimes fails.

My invention has for its object to overcome these drawbacks. This object is obtained primarily by embedding two conductors in the upper heddle bar these conductors being insulated from one another and from the bar and the upper edges of which project beyond the bar in such a manner that they are conductively connected by the upper eye of the heddles when the latter are hanging therefrom. Advantageously the heddle bar has a U-shaped cross section and is open on its upper side, whilst the two conductors are arranged symmetrically to the vertical middle

plane of the bar. This arrangement secures a reliable conductive connection of the two conductors by the upper eyes of the heddles in the hanging position. This effect may be further improved by making the upper portion of the eyes of the heddles that establish this electric contact being roof-shaped, so that the eyes ride so to speak on the two conductors and interconnect them with certainty.

The leaf of such a loom is provided with suitable contact pieces that in a determined position of the leaf close a circuit through the conductors. Now, as an accumulation of dust on all parts of the loom is unavoidable, the danger exists of the contact pieces failing to function. In order to overcome this trouble, according to my invention, each of the resilient contact pieces raising and lowering with the leaf, ends in a downwardly directed point which comes into correct conductive contact with the appurtenant stationary contact piece even if the latter is covered with wool dust or the like.

In order that my invention may be more easily understood, some preferred embodiments of the same are illustrated by way of example in the drawings which accompany and form part of this specification. In these drawings

Figure 1 shows a leaf in front view,

Figures 2 to 5 are sections through the upper bar in different positions, on an enlarged scale,

Figures 6 to 9 are similar sections, showing heddles having modified upper eyes, and

Figures 10 and 11 show a detail in two different positions.

While the leaf 12 is of the usual design, the upper bar 13 has a U-shaped cross section and embedded in it two conductors 14 and 15. These conductors are arranged symmetrically to the vertical middle plane of bar 13 and their upper edges project so far beyond the latter that when the upper eye 16 of one of the heddles 17 rests on the bar 13, as is to be seen from Figures 2, 4, and 5, a conductive connection is established between the two conductors 14 and 15.

The conductor 14 is conductively connected

to a resilient contact piece 18 and the conductor 15 to a similar contact piece 19 arranged on the opposite side of the leaf. These contact pieces 18, 19 correspond to stationary contact pieces 20 and 21, respectively, which are located so as to establish contact and to cause a circuit to be closed through the conductors 14 and 15 when the leaf is in its lowermost position. The circuit thus closed 10 by the interconnection of the conductors 14 and 15 further includes the usual electric means (not shown) serving to stop the loom. The described device operates as follows: As long as the warp-threads one of which 15 is indicated in each of the Figures 2 to 4 and denoted by 22, are intact, an electric connection is established between the conductors 14 and 15 by the upper eye 16, when leaf 12 raises, as shown in Figures 2, 4, as the thread 22 exerts a downward pull on the heddle 17. As soon however, as the leaf has passed, in 20 lowering the middle position, the thread 22 will act against the downward movement of the heddle, so that the upper eye is lifted and 25 the connection between the conductors 14, 15 interrupted, as shown in Figure 3. Now, as the contact pieces 18, 19, 20, 21 are in respective connection only with the leaf in the lowermost position, while all of the eyes 16 30 normally have the lifted position shown in Figure 3, the circuit is permanently interrupted. When however a warp-thread breaks, the eyes remain in the last-mentioned position upon the leaf 12 raising. Upon, 35 however, the leaf 12 lowering, no upward push is exerted on a heddle the thread of which is torn, so that the respective eye 16 will remain in the position shown in Figures 2, 4, and 5, even when the leaf has attained its lowermost 40 position, see Figure 5. At this instant however the contact pieces 18, 19, 20, 21 come into contact with each other, current is fed to the conductors 14, 15, and as these conductors are 45 conductively interconnected by the eye 16 of the heddle 17 of the broken thread, the circuit including the stopping means is closed, the latter is actuated and stops the loom. As soon as the operator has repaired the broken 50 thread, the loom operates anew as above described, until with the next breakage of a thread the stopping device acts in the same manner.

As can be seen from the foregoing, the described arrangement is extraordinarily simple and reliable in action, as the upwardly directed contact points of conductors 14, 15 and eyes 16 are not rendered inoperative by fibre dust and the like. Besides, the attendance of the loom does not require any increased work or attention, as it differs in no way from that of a loom not fitted with a stopping mechanism.

In the embodiment illustrated in Figures 6 to 9 the upper portion of the eye 16 of each heddle 17 has not a round shape, as has been

hitherto usual, but according to my invention this portion has a roof-shaped configuration. Therefore, as soon as the heddle is hanging from the bar 13, as shown in Figures 6, 8, and 9, the two legs 23, 24 of this roof-shaped upper eye portion come to rest on the projecting conductors 14, 15 and interconnect them electrically. Any failure of this conductive connection is absolutely impossible, as on the one hand these legs 23, 24 are resilient and have on the other hand the tendency to center the eye relatively to the two conductors, so that their middle plane always coincides with that of the eye. Because this is the case, a conductive connection between the two conductors is also warranted, as soon as they become energized by the closure of the contact piece 18, 20 and 19, 21. The angle formed by the legs 23, 24 depends on the section of the upper bar 13 and of that of the two conductors. Generally an angle of about 60 degrees will be of advantage, so that the roof corresponds to an equilateral triangle, whereby a particularly satisfying contact is warranted. Of course, I do not confine my invention to this modification, in the contrary, it includes any type of roof-shaped configuration of the upper eye of heddles that establish electric contact.

As to be seen from Figures 10 and 11, the electric contact pieces 18, 19 fixed on leaf 12 may further end in a point 25 and 26, respectively. This shape establishes a correct conductive contact between contact pieces 18, 19 and stationary pieces 20, 21 even in case fibre dust or the like has deposited on the latter, as the points 25, 26 penetrate even the thickest dust layer. Figure 11 shows one of the pairs of contact pieces 19, 21 in the closed position, in which the point 26 is urged by spring 27 against the stationary piece 21 and thus establishes an absolutely certain conductive connection.

What I claim and desire to secure by Letters Patent, is:—

1. In an electric stop motion device for looms a leaf with an upper heddle bar of U-shaped cross section, two electric conductor bars embedded in said heddle bar insulated from each other and from said heddle bar, their upper portions extending above the insulation and the heddle bar, heddles embracing said heddle bar with their upper eyes and riding upon said conductor bars if unsupported, contacts moving with said heddle bar and electrically connected to said contact bars, and corresponding fixed contacts, said movable contacts establishing electric connection with said fixed contacts if the frame is in its lower position.

2. In an electric stop motion device for looms a leaf with an upper heddle bar of U-shaped cross section, two conductor bars embedded in said heddle bar insulated from each other and from said heddle bar, their

upper portions extending symmetrically above the insulation and the heddle bar, heddles embracing said heddle bar with their upper eyes and riding upon said conductor bars if unsupported, the upper part of said eyes having the shape of an inverted V, resilient contacts moving vertically with said heddle bar and electrically connected to said conductor bars, and corresponding fixed contacts, said movable contacts establishing electric connection with said fixed contacts if the frame is in its lower position.

3. In an electric stop motion device for looms a leaf with an upper U-shaped heddle bar, two conductor bars embedded in said heddle bar insulated from each other and from said heddle bar, their upper portions extending above the insulation and the heddle bar, heddles embracing said heddle bar with their upper eyes and riding upon said contact bars if unsupported, the upper part of said eyes having the shape of an inverted V, resilient pointed contacts moving vertically with said heddle bar and electrically connected to said contact bars, and corresponding fixed contacts, said movable contacts establishing electric connection with said fixed contacts if the frame is in its lower position.

30 4. In a device of the character described a leaf having an upper heddle bar of U-shaped cross section, two conductor bars symmetrically embedded in said heddle bar insulated from said bar and from each other, their upper parts extending beyond the insulation, resilient pointed moving contacts on said heddle bar, each contact being electrically connected to one of said conductor bars, stationary contacts corresponding to said moving contacts, and heddles with their upper eyes embracing said heddle bar and riding on said contact bars in unsupported position, said eyes having symmetrical straight and inclined upper portions for making contact with said conductor bars.

45 5. In an electric stop motion device for looms, a leaf with an upper heddle bar, two electric conductor bars embedded in said heddle bar insulated from each other and from said heddle bar, heddles embracing said heddle bar with their upper eyes, said upper eyes being formed of an inverted V symmetrical with the longitudinal axis of said heddle, each leg of said V being resilient and riding on one of said conductors if unsupported, contacts moving with said heddle bar, and corresponding fixed contacts, said movable contacts establishing electrical connection with said fixed contacts if the frame is in its lower position.

In testimony whereof I affix my signature.
THEODOR CURT WAGNER.
